UNITED STATES PATENT OFFICE.

JOHN SZEPESSY, OF CENTERVILLE, MARYLAND.

SHIP CONSTRUCTION.

1,105,009.

Specification of Letters Patent. Patented July 28, 1914.

Application filed April 1, 1914. Serial No. 828,739.

To all whom it may concern:

Be it known that I, JOHN SZEPESSY, a subject of the King of Hungary, residing at Centerville, in the county of Queen Anne's 5 and State of Maryland, have invented certain new and useful Improvements in Ship Construction, of which the following is a specification.

This invention relates to new and useful 10 improvements in ship construction.

The primary object of this device is to provide such vessels as life boats with a shiftable ballast which will automatically remain in its proper position regardless of 15 the effect of the waves and the elements exerted upon the vessel.

A further object is to provide a shiftable ballast for all kinds of floating crafts of such a design as to normally shift to a bal- 20 ancing position at the bottom of the boat.

A still further object is to provide a shift- 25 able ballast mounted upon upright members carried by the bottom of a boat and having suitable guides and limiting means for such ballast during its movement.

With these general objects in view and others that will appear as the nature of the invention is better understood, the same consists in the novel combination and arrangement of parts hereinafter fully described, 30 illustrated in the accompanying drawings and pointed out in the appended claims.

In the drawings forming a part of this application and in which like designating 35 characters refer to corresponding parts throughout the several views: Figure 1 is a side elevation of a boat having the present device mounted therein, parts being broken away. Fig. 2 is a transverse vertical sec- 40 tional view thereof taken through one of the mounting means for the ballast member. Fig. 3 is a perspective view of an end por- 45 tion of the ballast member and the means carried thereby. Fig. 4 is a vertical sectional view upon line IV—IV of Fig. 2, and Fig. 5 is an enlarged horizontal sectional view taken upon line V—V of Fig. 4.

Referring more in detail to the drawings, 50 the ballast member 10 is illustrated as having upwardly projecting posts 11 adjacent its opposite ends and provided with conical sockets 12 for receiving the upright posts 13 mounted in the block 14 upon the keel portion 15 of the hull 16 and whereby the

ballast member is shiftably suspended. The 55 outer sides of the ballast member are curved as at 17 for conforming to the shape of the inner side of the hull while arcuate slots 18 open at their tops are provided adjacent the opposite edges of the ballast member 60 and adapted to receive downwardly project- ing sheathing strips 19 slidably therein. Outwardly projecting arms 20 are carried by the posts 11 adjacent to the tops thereof and the outer free ends of said arms are 65 slidably mounted within the U-shaped blocks 21 secured at opposite points interiorly of the vessel and to said lining sheath- ing 19 thereof. The opposite sides of the opening 22 of the blocks 21 are provided 70 with anti-friction balls 23 secured in race- ways 24 in said block by means of keeper strips 25. A cross bar 26 having a central neck 27 provided with a downwardly ex- 75 tends finger 28 is adapted to be mounted upon each of said posts 11 by the seating of the finger 28 within the central tapered socket 29 formed in the top of each post.

By this construction of device it will be seen that the ballast member 10 is free to 80 swing upon the upright members 13 whenever the hull is shifted by the waves while the ends of the cross arm 20 are freely slid- 85 able upon the ball bearings of the side blocks 21 and the sidewise movement of the ballast is limited by the free opposite ends of the top bar 26, the ends of which are adapted to engage the inner wall of the hull upon extreme shifting of the ballast mem- 90 ber. The sliding engagement of the sheath- ing 19 within the slots 18 of the ballast member presents an unbroken interior sur- 95 face for the boat. It will thus be evident that the contents of the boat which is positioned upon the member 10 interiorly of the boat will at all times retain its stable posi- 100 tion by reason of the upper surface of the ballast member retaining its horizontal position and thus the contents of the boat will be unaffected by the sidewise rolling move- ment of the hull and will assist the boat in maintaining its equilibrium upon the waves.

While the forms of the invention herein shown and described are what are believed to be preferable embodiments thereof, it is 105 nevertheless to be understood that minor changes may be made in the form, propor- tion and details of construction without de-

parting from the spirit and scope of the invention as set forth in the appended claims.

What is claimed as new is:—

- 5 1. A device of the class described comprising a hull, upright posts mounted upon the keel portion of the hull, a ballast member having hollow posts upwardly extending thereon and mounted upon said upright posts, outwardly extending arms adjacent the tops of said hollow posts, anti-friction U-shaped blocks oppositely positioned interiorly of the hull and adapted for the sliding reception of the free opposite ends of said arms, said ballast member provided with arcuate slots adjacent the opposite upper edges thereof, inner sheathing strips within said hull adapted for sliding reception within said slots and a removable cross 10 bar upon each of said hollow posts adapted for limiting the lateral movement of said ballast member.
- 15 2. A device of the class described comprising a hull, spaced blocks positioned interiorly and mounted upon the keel portion thereof, upright posts mounted in said blocks, a shiftable ballast member having posts mounted thereon provided with conical sockets therein adapted for seating over said upright posts, said ballast member having curved outer faces and provided with arcuate slots spaced inwardly from said faces, inner sheathing strips carried by said hull and adapted for sliding reception with- 20 25 30

in said slots, U-shaped anti-friction guide blocks carried at opposite points within said hull, oppositely projecting arms carried by said posts and slidably engaging within said guide blocks, upper stop bars adapted to engage the inner sides of the hull upon a tilting of the ballast member, a projecting finger upon each of said stop bars, a depressed socket in the top of each of said posts of the ballast member and adapted for the seating reception of said fingers therein. 35 40 45

3. A device of the class described comprising a hull, upright posts rigidly mounted interiorly upon the keel portion thereof, a ballast member within said hull and having upwardly projecting conical sockets therein 50 for the mounting reception of said upright posts, anti-friction guide means for said ballast member carried by said hull, said ballast member provided with arcuate slots adjacent its opposite edges, inner sheathing strips 55 having their lower edges slidably received within said slots and limiting stop bars carried by said ballast member and adapted for engaging the inner sides of said hull upon the tilting movement of said ballast 60 member.

In testimony whereof I affix my signature in presence of two witnesses.

JOHN SZEPESSY.
